UNITED STATES PATENT OFFICE.

WILLIAM B. CROSSING, OF WINNIPEG, MANITOBA, CANADA.

TIE-LAYING MACHINE.

Application filed September 14, 1922. Serial No. 588,280.

To all whom it may concern:

Be it known that I, WILLIAM B. CROSSING, of the city of Winnipeg, Province of Manitoba, Dominion of Canada, a subject 5 of the King of Great Britain, have invented certain new and useful Improvements in Tie-Laying Machines; and I do hereby declare that the following is a full, clear, and exact description thereof.

10 My invention relates particularly to machines for laying ties in the construction of railway tracks and has for its object to provide a machine of this type which may be operated fifty feet in advance of the track 15 layer, and which when in motion will constantly and uniformly deposit the ties upon the road bed with more precision than has been obtainable with machines of this type in use in the past.

20 A further object of this invention is to produce a machine of simplified construction and comparatively low cost and one which may be operated with equal facility rounding curves whether travelling in a 25 straight line or rounding a curve.

For full comprehension, however, of my invention, reference must be had to the accompanying drawings in which similar reference characters indicate the same parts, 30 and wherein:

Figure 1, is a plan view of a tie laying machine constructed according to my invention;

Figure 2 is a horizontal sectional view 35 taken on line 2—2 Figure 3;

Figure 3 is a side elevation of the machine; and

Figure 4 is a fragmentary side elevation 40 of the transverse tram and deflector which cooperates therewith.

The accompanying drawings illustrate the preferred embodiment of my invention. This embodiment consists of a machine adapted to be propelled in advance of the track layer (not shown) through the medium of thrust beams extending from the head end of the pioneer car to the rear end of the layer. This tie laying machine comprises a chassis 2 consisting of side sills 3 and 4, rear end sill 5, front end sill 6, transverse braces 7, longitudinal braces 8 extending between the sill 6 and the cross brace 7 immediately adjacent, and a circular track 9 of channel cross-section positioned within 55 the space bounded by the braces 8, front end sill 6 and the cross brace 7 nearest thereto.

The rear end of the chassis is braced by diagonal stays 10 and 12.

This chassis is supported by rear wheels 25 positioned exteriorly of the chassis upon an axle 26 and the front wheels 27 mounted on an axle 28 having rollers 29 at its opposite ends adapted to revolve in the circular track 9, the front wheels being of much smaller diameter, than the rear wheels and 60 encircled by the track. A steering mechanism is provided for these front wheels to the left or to the right, and include a steering wheel 30 mounted on the upper end of the vertical steering post 31 the lower end of 65 which is operatively connected to the axle.

Supported upon the chassis are the tie feeding trams, one longitudinally disposed and indicated at 14 and the other transversely disposed and indicated at 15. The 70 supporting structure comprises uprights 16 supporting at their upper ends a rectangular frame 17 which is braced by transverse members 18 and diagonal stays 19.

The longitudinal tram 14 is located at one 75 side of the machine and comprises a pair of parallel longitudinal members 20 and 21 positioned edge up upon the braces 8 and secured thereon by brackets or U bolts 22 and transversely braced as at 23. These members are spaced apart just sufficiently to accommodate the width of the tie and carry 80 between them a series of transversely disposed rollers 40. Each of these rollers comprises a stub shaft having its end journaled 85 in the members 14 and extending therebetween and carrying a plurality of uniformly spaced discs 41 which are adapted 90 to engage the underside of the tie as it is fed to the magazine to be hereinafter described, the discs of one roller being in staggered relation with those of the adjacent rollers. These rollers are driven in unison 95 in a clockwise direction by a sprocket chain 43 encircling a sprocket wheel 44 on an extension of each of the stub shafts 40, the shaft 40 nearest the front of the machine being extended outwardly relatively to the machine frame and carrying a bevel gear 45 which is in intermeshing relation with a 100 similar gear 46 keyed upon an elongated shaft 47 journaled in brackets 48. This shaft may be driven by an engine mounted upon the tie layer or by the same power means which is employed for feeding the 105 ties onto the tie layer.

The transverse tram 15 is positioned at the

front of the machine and is perpendicularly disposed to the longitudinal tram, each tie as it leaves the latter being passed on to the transverse tram for the purpose of swinging the tie around to position transversely to the direction of travel of the machine. The transverse tram consists of a plurality of rollers 50 of similar construction to those constituting the longitudinal tram, the stub 5 shafts 51 of the rollers being journalled in bearings 52 mounted upon a transverse member 53. These rollers are adapted to be driven in unison by a sprocket chain 54 encircling sprocket wheels 55 upon the roller 10 stub shafts and they are driven by the same means as that employed for driving the longitudinal tram, a sprocket wheel 56 being keyed upon the adjacent end of the shaft 8 and rotatably connected to a similar sprocket 20 59 upon the roller stub shaft furthest from the shaft 8 through a sprocket chain 60.

In order to facilitate the swinging of each tie from longitudinal to transverse positions and to cause the discharge of each tie into 25 the magazine after it reaches a predetermined point in its travel upon the transverse tram a curved deflector plate 70 is mounted in position extending from the outer side of the front end of the longitudinal tram to a 30 point at the opposite side of the machine. This plate is of greater length than width and horizontally disposed with its side edge up, and it is braced by uprights 71.

The magazine which is adapted to carry a 35 plurality of transversely positioned ties consists of an inclined floor 73 extending from side to side of the machine frame and from a point beneath the transverse tram downwardly to a point substantially midway the length 40 of the machine in plan view and it is provided with ends 74 for preventing endwise displacement of the ties when in position thereon.

A rotary distributor extends across the 45 machine frame in juxtaposition with the lower end of the magazine and is constructed and arranged to successively pick up the ties in the magazine and distribute them along the road bed at predetermined intervals.

50 This distributor consists of a shaft 80 the ends of which are journalled in bearings 81 and 82 supported upon the chassis and discs 83 and 84 keyed upon the shaft within the chassis and adjacent the side sills of the latter. Each of these discs carries a plurality 55 of uniformly spaced radial fingers 85 which, during the rotary movements of the shaft engage the underside of the lowermost tie in the magazine at each end, this being permitted as the extreme lower end of the magazine is extended between the discs as at 86 and provided with an abutment 87 so that when the lowermost tie is in position bearing against this abutment its ends project beyond 60 the ends of the extension in the path of the

80 fingers 85. The ties are selected singly by the fingers and carried around therewith as the distributor is rotated. In order to prevent each tie becoming displaced from the distributor before it reaches the point of 70 travel at which it is to be deposited upon the road bed a retaining plate 90 is mounted in juxtaposition with the distributor at its rear side and extends completely across the chassis. This plate is carried by arms 91 secured to one of the cross braces and its lower end 75 is curved beneath the distributor as at 92 thereby preventing the ties leaving the distributor until they are substantially beneath the same.

85 This distributor is driven by the rear axle and is operatively connected thereto through a spur gear 95 mounted on an extension of the shaft 80 and intermeshing with a second spur gear 96 mounted upon a stud 97 journalled in bearings 98. A sprocket wheel 99 is keyed upon this shaft and is rotatably connected to a sprocket wheel 100 on the axle 26 through a sprocket chain 101. As the tie 90 layer is propelled along the road bed the sprocket wheels 100 and 99 and the spur gear 96 are rotated in a clockwise direction while the gear 95 and consequently the distributor are rotated in a counter clockwise direction, and the drive is so timed that the 95 ties when deposited upon the road bed will be spaced apart the required distance so that further positioning of the ties is unnecessary, the rails being positioned thereon in the positions which they assumed when deposited. 100

What I claim is as follows:—

1. In a tie laying machine a longitudinally disposed tram; a second tram located in position adjacent the forward end of the first mentioned tram and disposed perpendicularly thereto, and a deflector adapted to coact with said trams in causing a tie moving in an endwise direction along the longitudinal tram to assume a transverse position relatively to the direction of travel of the machine as such tie is fed to the transverse tram, said deflector consisting of a curved plate mounted edge up upon the frame in juxtaposition with the second tram. 110

2. In a tie laying machine the combination with a tie magazine, of a rotary distributor constructed and arranged to consecutively take ties from the said magazine. 115

3. In a tie laying machine the combination with a tie magazine, a rotary distributor constructed and arranged to select ties from the said magazine; and means for feeding ties to the magazine, said means including a longitudinally disposed tram and a transversely disposed tram located adjacent the forward end of the longitudinal tram and in juxtaposition with the magazine, and fixed means coacting with the trams for discharging the ties therefrom to the magazine. 120

4. In a tie laying machine the combination 125

with an inclined magazine, a rotary distributor located at the lower end of the magazine and adapted to select ties therefrom and discharge the same upon the road bed; means for rotating said distributor and means for feeding ties to the magazine.

5. In a tie laying machine the combination with the frame thereof and means for supporting the latter including a rear axle and rear supporting wheels; of an inclined magazine; a rotary distributor located at the lower end of the magazine and adapted to select ties therefrom and distribute the same upon the road bed; said distributor consisting of a shaft transversely journaled in the said frame and having a plurality of uniformly spaced radial projections adjacent each end; means for driving said distributor; and means for feeding ties to the magazine.

6. In a tie laying machine the combination with the frame thereof; including a circular track; means for supporting the same consisting of a rear axle extending across the rear end of the frame; rear wheels of comparatively large diameter mounted upon the extreme ends of said axle and exteriorly of the frame; a front axle diametrically disposed within said circular track rollers upon the extreme ends of said axle and adapted to revolve upon the track, and a pair of front wheels mounted upon said axle in position encircled by the track, and steering mechanism operatively connected to said front axle; a tie magazine, a rotary distributor adapted to select ties from the magazine and distribute them upon the road bed and means for feeding ties to the magazine.

7. In a tie laying machine the combination with a tie magazine; a rotary distributor constructed and arranged to select ties from the magazine and deposit them at intervals upon the road bed and means for preventing

displacement of the ties from the distributor during travel around the same, and means for driving said distributor.

8. In a tie laying machine the combination with a tie magazine; a rotary distributor constructed and arranged to select ties from the magazine and deposit them at intervals upon the road bed and means for preventing displacement of the ties from the distributor during travel around the same, said means consisting of a plate disposed parallel to the distributor and extending slightly beneath the same.

9. In a tie laying machine the combination with a magazine consisting of an inclined floor having an extension at its lower end carrying an abutment against which the lowermost tie in the magazine is adapted to bear; a rotary distributor including tie selecting members located at opposite ends of the extension and adapted to "pick up" a tie resting thereon and means for rotating said distributor.

10. In a tie laying machine the combination with a magazine consisting of an inclined floor having an extension at its lower end carrying an abutment against which the lowermost tie in the magazine is adapted to bear; a rotary distributor including tie selecting members located at opposite ends of the extension and adapted to "pick up" a tie resting thereon and means for rotating said distributor, and means for preventing displacement of each tie from the distributor during travel around the same.

In testimony whereof I have signed my name to this specification in the presence of two witnesses.

WILLIAM B. CROSSING.
